Patented Dec. 28, 1920.

Inventor
Joseph Soss

By his Attorney

Edgar V. Sted.

UNITED STATES PATENT OFFICE.

JOSEPH SOSS, OF NEW YORK, N. Y.

HINGE.

1,363,371.

Specification of Letters Patent. Patented Dec. 28, 1920.

Application filed December 19, 1919. Serial No. 346,081.

To all whom it may concern:

Be it known that I, Joseph Soss, a citizen of the United States, and residing at New York, in the county of New York and State of New York, have invented certain new and useful Improvements in Hinges, of which the following is a specification, such as will enable those skilled in the art to which it appertains to make and use the same.

10 This invention relates to hinges and particularly to devices of this class designed to be used in connection with the doors of motor vehicles but which may also be used in connection with other doors or swinging members, and the object of the invention is to provide a die cast hinge or hinge member of the class specified, and means for reinforcing and strengthening said hinge or hinge member by a sheet metal strip fashioned to conform with the general form of the hinge or hinge member thus materially decreasing the cost of production of the hinge member and yet producing a strong and durable article; and with this and other 20 objects in view the invention consists in a device of the class and for the purpose specified constructed as hereinafter described and claimed.

The invention is fully disclosed in the following specification, of which the accompanying drawing forms a part, in which the separate parts of my improvement are designated by suitable reference characters in each of the views, and in which:

35 Figure 1 is an edge view of one of my improved hinges showing the separate members thereof:

Fig. 2 a perspective view of one of the hinge members shown in Fig. 1;

40 Fig. 3 a partial section on the line 3—3 of Fig. 2;

Fig. 4 a partial section on the line 4—4 of Fig. 2;

Fig. 5 a partial section on the line 5—5 45 of Fig. 3.

In Fig. 1 of the drawing I have illustrated a complete hinge of the general form to which this invention relates particularly, and at 10 is shown the member of the hinge which is secured to the door frame and at 11 50 the member which is secured to the door, said members being secured together by a hinge pin 12 in the usual manner.

My invention relates particularly to the 55 construction of the hinge member 11 which is shown in detail in Figs. 2 to 5 inclusive.

Said member comprises an elongated plate 13, one end portion of which is bent into hook-shaped form as shown at 14 in Figs. 1 and 3, and the free end of the hook-shaped end portion is provided with an approximately cylindrical portion 15. The hook-shaped end portion 14 of the member 11 is recessed at the opposite sides of the longitudinal center thereof as shown at 16 to receive the hook-shaped end portion 17 of the member 10 of the hinge as illustrated in Fig. 1, and the recesses 16 divide the cylindrical end 15 of the hinge member 11 into a central bearing 18 and end bearings 19, all of which are 60 apertured as shown at 20 in Fig. 5 to receive the hinge pin 12.

The plate 13, or the straight end portion 21 thereof is also preferably provided with a plurality of countersunk screw apertures 75 22 through which screws are adapted to pass in securing the member 11 to a door or other swinging member. The cylindrical end 15 of the hook-shaped end portion 14 is provided with an offset or shoulder portion 80 23, which extends the full width of the plate 13, or the cylindrical portion 15 thereof, as clearly shown in Fig. 2, and this shoulder operates in connection with a corresponding shoulder 24 formed on the hinge member 10 to limit the swinging movement 85 of the hinge member 11.

The above description clearly sets out the general form of the hinge member 11 and its connection with and operation in connection 90 with the hinge member 10, and while the general form and construction of the separate hinge members is old and well known, my invention relates particularly to the construction or formation of the hinge member 11 by die-casting the same and suitably reinforcing and strengthening the hinge member by a sheet metal strip fashioned to conform with the general form of the hinge member, and which is wholly or partially 95 embedded in and forms part of the hinge member.

In Figs. 1 to 5 inclusive I have shown a reinforcing sheet 25 which is located on the outer face of the hinge member 11 and extends from the straight end portion 21 thereof to the shoulder 23 on the cylindrical portion 15. The sheet 25 is preferably provided at spaced intervals with apertures 26, one of which is shown in Fig. 3 and two of 105 which are shown in Fig. 4, through which the metal of the hinge member 11 passes in 110

the casting or formation of said hinge member. The opposite side edge portions of the sheet 25 are flanged inwardly as shown at 27 to form a channel of the sheet 25 and to 5 inclose the top and bottom faces of the member 11, as clearly illustrated in Figs. 2 and 4 of the drawing. The flanges 27 of the sheet 25 are fashioned to conform with the shape of the hook-shaped end portion 14 10 and cylindrical portion 15 of the hinge member 11 as shown at 28 in Figs. 1, 2 and 5 of the drawing, and said flanges are provided with apertures 29 which correspond with the apertures 20 in the bearings 18 and 15 19 of the cylindrical portion 15. The sheet 25 is also provided with apertures 30 in line with the screw apertures 22.

The sheet 25, or that part thereof, which passes around the hook-shaped end portion 14 and cylindrical portion 15 of the hinge member 11 is cut centrally thereof and depressed inwardly to form a central reinforcing member 31 which is of the same transverse width as the central bearing member 18 and which, in the construction shown in Figs. 1 to 5 inclusive, forms a partial facing for the aperture 20 on the bearing member 18 as shown at 32. The reinforcing member 31, as will be evident, serves 25 to strengthen the central part of the cylindrical portion 15 of the hinge member, or the bearing 18 thereof. It will be understood that the bearings 19 are reinforced and strengthened by the top and bottom 30 flange portions 28.

From the foregoing it will be seen that in the formation of the hinge member 11, I first provide a sheet metal strip which is fashioned to the desired form, and this sheet 40 is then placed in a suitable mold or die into which metal is forced, and the result of this operation will produce the complete hinge member with the reinforcing sheet forming part thereof and the apertures 20 and screw apertures 22 also formed therein. In making up a hinge member in the manner herein shown and described, it will be apparent 45 that the cost of production is materially de-

creased and yet I produce a strong and durable hinge member, and by manufacturing 50 these hinge members in the manner set out, I can also materially increase the output as the necessity of machining, boring and drilling, which is the present procedure in the making of hinges, or hinge members in 55 the class under consideration, is obviated. It will also be understood that while I have shown a specific form of reinforcing sheet which is partially embedded in the hinge member and have also shown a hinge mem- 60 ber of specific shape or form, my invention is not necessarily limited in these respects, and various changes in and modifications of the construction herein shown and described may be made, within the scope of the ap- 65 pended claims, without departing from the spirit of my invention or sacrificing its ad- vantages.

Having fully described my invention, what I claim as new and desire to secure 70 by Letters Patent, is:—

1. A die cast hinge member of the class described composed of a die cast body comprising an elongated portion at one end of which is an enlarged portion extending at 75 an angle to said elongated portion, and a sheet of metal forming a facing for one side face and the top and bottom faces of said die cast body.

2. A die cast hinge member of the class 80 described composed of a die cast body one end of which is enlarged and extends at an angle to the main body portion, recesses formed in one side face of the enlarged end portion, and a sheet of metal forming a 85 facing for the other side and face of said die cast body.

In testimony that I claim the foregoing as my invention I have signed my name in presence of the subscribing witnesses this 90 16th day of December, 1919.

JOSEPH SOSS.
